F. W. Miller, Jr.

UNITED STATES PATENT OFFICE.

BENNETT G. JANSSON, OF MALDEN, MASSACHUSETTS, ASSIGNOR TO BLAKE SIGNAL AND MANUFACTURING CO., OF BOSTON, MASSACHUSETTS, A CORPORATION OF MASSACHUSETTS.

INSULATED CLEAT.

1,105,664.

Specification of Letters Patent. Patented Aug. 4, 1914.

Application filed July 29, 1912. Serial No. 712,104.

To all whom it may concern:

Be it known that I, BENNETT G. JANSSON, residing at Malden, in the county of Middlesex and State of Massachusetts, have invented certain Improvements in Insulated Cleats, of which the following is a specification.

The present invention relates to cleats for holding wires in position on the walls of buildings and to means for making them.

My improved cleat is made from any suitable material which is not a good conductor of electricity, but I prefer to make it from short pieces or blanks of hard straight-grained wood such as maple of any preferred cross-section, which have a hole bored in the direction of their fiber into which is driven a closely fitting nail, after which the blank is placed between dies leaving one end rounded or convexed while the opposite end is concaved with a central teat inclosing the nail. All of which I will now proceed to describe and point out specifically in the appended claim.

In the drawings, which form a part of and illustrate the specification,—Figure 1 is an elevation of a round piece of insulating material such as wood, and a^2 a^2 are short pieces or blanks cut from one end thereof. Fig. 2 is an end view of a blank with a hole a^3 bored therein. Fig. 3 is a section of a blank b with a nail a^4 driven through the hole a^3 , and Fig. 4 is a perspective view of the same. Fig. 5 is an elevation of a die c , and Fig. 6 is a sectional view of a die d with a blank b inserted into the sunken hollow d^2 . Fig. 7 is a sectional view of the die c and of the die d as they are forced into each other with the blank b between them.

Fig. 8 is a perspective view of the completed cleat b^2 . Fig. 9 is a sectional view of the completed cleat b^2 . Fig. 10 is a plan view of the cleat b^2 holding the wires w w in position.

In the drawings a is a piece of round rod of wood and a^2 a^2 are blanks sawed from the rod to form the cleats, in each of which a hole a^3 is bored to receive the nail a^4 which fits tightly therein.

The means for completing the cleat consists of the two dies c and d ; the former is made with a convex end into which is bored a hole c^2 having an enlarged opening at its lower end. The lower die d has a hole d^2

sunk in its upper side with a diameter of 55 the size of the blanks a^2 and its bottom is made convex to form the upper surface of the cleat, and its depth is somewhat more than the thickness of the blank. These dies are placed in a power press in a manner well 60 understood so that the lower one d is fixed and the upper one c movable; and when a blank a^2 is to be formed it is placed in the lower die d as shown in Fig. 6, and the upper die forced downward so that the nail a^4 65 enters the hole c^2 thereof, and the end of the die enters the hole d^2 of the die d as shown in Fig. 7, and the lower end of the blank is forced to conform to the curved bottom of the die d while its upper end is squeezed to 70 conform to the end of the die c and make the concave depression e^2 and form the teat-like portion e^3 around the nail a^4 ; at the same time the head a^5 of the nail is embedded in the concave surface of the cleat. 75 Thus by one operation the blank is shaped by pressure into the cleat, the material thereof being forced into the form shown in the Figs. 8 and 9; and when the cleat is driven into a base to hold insulated wires 80 w w in place the central teat e^3 insulates the nail a^4 from them, and the edges e^4 hold the same to the base. The wires w are of course usually covered with insulating material as indicated in Fig. 10, which insulating material is soft enough to permit the edge e^4 to 85 sink somewhat thereinto. As best shown in Fig. 9, the teat e^3 , while projecting far enough to act as a spacer to hold the two wires w separated, is not long enough to 90 reach the surface of the support into which the nail is driven before the wires are clamped or gripped by the edge e^4 . In other words the teat e^3 is not in excess of 95 the radial distance from it to the biting or gripping edge e^4 and, therefore, said teat cannot oppose the driving of the nail into the supporting surface before the edge e^4 reaches a position to perform its function. Since the said edge e^4 is continuous, the device can be used without any preliminary arrangement about its axis. In other words 100 it can be driven regardless of how the cleat may be turned.

I claim as my invention:—

A device of the character described, comprising a nail having an insulating cleat compressed tightly thereon, the head of the

nail being embedded in one face of the cleat, the other face of the cleat being concaved and having a circular continuous marginal edge to grip wires, the concaved face of the cleat having a central teat surrounding the shank of the nail, said teat having a length not exceeding the radial distance from it to the gripping edge, whereby two wires may be gripped against a supporting surface and held separated by the teat without having said teat oppose the driving of the nail into

the supporting surface before the said edge has gripped the wires.

In testimony whereof, I have signed my name to this specification in the presence of 15 two subscribing witnesses, this 25th day of July, 1912.

BENNETT G. JANSSON.
